Patented June 15, 1965

201,408

HYDROFOIL CRAFT

Paul A. Scherer, "Marietta," Bell Station Road,
Glenn Dale, Md.

Filed June 23, 1964, Ser. No. 80,532

Term of patent 14 years

(Cl. D71—1)

FIG. 2

Des. 201,408

PAGE 3

FIGURE 1 is a perspective of the hydrofoil craft;
FIGURE 2 is a top plan of the hydrofoil craft;
FIGURE 3 is a side elevation of the hydrofoil craft;
FIGURE 4 is a front elevation of the hydrofoil craft;
FIGURE 5 is a side elevation, showing the canopy open;

FIGURE 6 is a front elevation, showing the displacement elements in elevated position.

The rear of the craft, not shown, is substantially plain, and the side opposite that shown in FIGURES 3 and 5 is substantially a mirror image of the side shown.

I claim:
The ornamental design for a hydrofoil craft, as shown and described.
